UNITED STATES PATENT OFFICE.

GEORGE HERBERT CLAPHAM, OF MANCHESTER, ENGLAND.

HOLDER FOR EYEGLASSES AND THE LIKE ARTICLES.

1,140,024.

Specification of Letters Patent.

Patented May 18, 1915.

Application filed May 26, 1910. Serial No. 563,580.

To all whom it may concern:

Be it known that I, GEORGE H. CLAPHAM, a subject of the King of England, residing at 56 King street, Manchester, England, have invented a new and useful Improvement in Holders for Eyeglasses and the like Articles, of which the following is a specification.

This invention relates more particularly to what are known as automatic eyeglass holders, and it has for its object to so construct them as to enable the recoil or retraction, of the chain, to which the eyeglass is attached, to be checked at any desired length and so prevent the eye-glass flying back and injuring the user, or becoming damaged. The chain is controlled by a spring drum, or barrel in the usual manner, and the holder, or case, is provided, on its circumference, with a circular orifice for the passage of such chain, when drawing it out, or when restoring or retiring it; but according to arrangement the spring drum or barrel is furnished with a check, or detent, which is liable to derangement the result then being that the chain, when drawn out, cannot be returned. Now, for the purpose of my invention, I dispense with this check or detent and I provide the hole or orifice, through which the chain or eye-glass carrier runs with an angularly shaped slot, preferably an elongated V-shaped one, which is advantageously arranged at a slight angle to the periphery of the barrel or drum, and serves to arrest the recoil, or return of the chain or eye-glass carrier. Thus, if the chain be left to itself after the disengagement or release of its controlling spring, when retiring the eye-glass, the said chain will be caught by one of its links, between the edges or jaws of the V-slot, and will be thereby arrested, so preventing it flying back suddenly and causing injury to the user, or damage to the eye-glass. Owing to the diagonal arrangement of the said V-slot it is in the line in which the hand moves when placing the eye-glasses on the nose. And in order that my invention may be clearly understood, I will now describe it fully with reference to the accompanying drawings, wherein:

Figure 1 is a perspective view showing a holder with the chain passing through the usual circular hole or orifice and free to be withdrawn or retracted, and Fig. 2 is a like view, but showing the chain arrested by one of its links, in the V-slot. Fig. 3 is an enlarged view of a portion of the holder or casing showing the opening therein for the passage of the chain or cord-like guard.

In these drawings, *a* is the holder, *b* the chain, or other carrier having projections on its length, and *c* the circular hole or orifice, *c*¹ is the elongated V-shaped slot terminating the orifice *c* and by means of which the chain or carrier *b* is, by one of its links or projections arrested. In order to effect the arrest of the chain at any desired length, it is merely necessary, when drawing it out, or when retiring it, to leave it to itself, when it will at once pass into the V-slot *c*¹, whereupon it will be caught by one of its links, between the jaws or edges of the said V-slot, and be thereby arrested, so checking its recoil or retraction.

It will be seen by reference to Fig. 3 that the enlarged or free passage portion for the guard, designated at *c*, and the contracted guard-checking portion *c*¹ constitutes a single unrestricted opening, without any partitions or projections therein, and which readily permit movement of the guard from the free passage to the contracted portion when one end of the guard is moved by the hand in a straight line or direction. In other words, it is not necessary to move the free end of the guard first in one direction and then in another direction in order to inter-lock or unlock or uncheck the guard with respect to the casing. This is a great advantage as it serves to facilitate withdrawal and winding of the chain without any unnecessary movement of the hand on the part of the user. It will also be seen that the walls of the free passage portion *c* merge into the walls of the contracted portion *c*¹ on gently curved cam-like lines, as indicated at *c*². These lines *c*² are substantially uniform on both sides and serve to guide the guard from the free passage to the guard-checking portion, upon movement of the free end of the guard, whether or not such movement of

the free end of the guard is accurately made or carried out. It will thus be seen that the portions *c* and *c'* present a single, unrestricted opening and not an opening having any restricting wall portion whatever to interfere with the free movement of the guard.

Obviously, the invention may be applied to similarly constructed spring controlled 10 holders for carrying pencil-cases, fountain-pens, keys, or such like articles.

Claims:

1. A device of the class described comprising in combination, a cord or chain-like 15 guard for connection with the article to be held, a casing, and a spring-controlled reel mounted in said casing and normally acting to reel-in the guard, said casing being provided with an aperture presenting a single, unrestricted and undivided opening for 20 passage of the guard, one portion of said opening being relatively enlarged with respect to the diameter of the guard to afford free passage therethrough, the other portion 25 of said opening being contracted in a V-shaped form to check the passage of the guard, the walls of the V-shaped portion merging into the walls of the free passage portion on gently curved lines.
- 30 2. A device of the class described comprising in combination, a chain or cord-like guard for connection with the article to be held, a casing, and a spring-controlled reel mounted in said casing and normally acting 35 to reel-in the guard, said casing having an elongated aperture presenting a single, undivided and unrestricted opening having an enlarged guard passage portion and a relatively contracted guard-checking portion, the walls of the free passage portion 40 converging substantially uniformly on both sides toward and merging into the walls of said contracted checking portion on gently curved guiding or cam-like lines.
- 45 3. A device of the class described comprising in combination, a cord or chain-like guard for connection with the article to be held, a casing, and a spring-controlled reel mounted in said casing and normally acting 50 to reel-in or wind in the guard, said casing having a single aperture for passage therethrough of the guard comprising an undivided opening having a free guard passage portion and a contracted guard checking portion, whereby movement of one end of 55 the guard in a straight direction will permit movement of the guard from one portion of the opening to the opposite portion thereof.
- 60 4. A device of the class described comprising in combination, a cord or chain-like guard for connection with the article to be held, a casing, and a spring-controlled reel in said casing normally acting to wind-in the guard, said casing having a single aper-

ture provided with a relatively enlarged 65 free passage guard portion and a relatively contracted guard checking portion with the walls of one portion merging into the walls of the other portion on gently curved lines to permit free lateral passage 70 of the guard from one portion to the other, the guard-checking portion being angularly disposed with respect to the normal line of travel of the guard.

5. A device of the class described comprising in combination, a casing, a spring-controlled reel rotatively mounted in said casing, and a chain attached at one end to said reel and having its adjoining links set in planes substantially at right angles to 80 each other, said reel being so arranged as to normally reel in said chain, said casing being provided with an oblong opening with rigid edges and having two portions in substantially longitudinal alignment with respect to each other, one portion of said opening being relatively enlarged with respect to the diameter of the chain both laterally and longitudinally of the longitudinal axis of the oblong opening to afford 85 free passage of the chain therethrough, the other portion of said opening having parallel edges and being restricted laterally to such an extent as to prevent the passage of the chain therethrough, the walls of said 90 restricted portion merging into the walls of said enlarged portion on gently curved lines to guide the chain into locked relation with said parallel edges.

6. A device of the class described comprising in combination, a casing, a spring controlled reel rotatively mounted in said casing, and a chain attached at one end to said reel, and having its adjoining links set in planes substantially at right angles to each 100 other, said reel being so arranged as to normally reel in said chain, said casing being provided with an oblong opening with rigid edges and having two portions in substantially longitudinal alignment with respect 105 to each other, one portion of said opening being relatively enlarged with respect to the diameter of the chain both laterally and longitudinally of the longitudinal axis of the oblong opening to afford free passage of the chain 110 therethrough, the other portion of said opening having parallel edges and being restricted laterally to such an extent as to prevent the passage of the chain therethrough, the walls of said restricted portion merging into the walls of said enlarged portion on gently curved lines to guide the chain into locked relation with said parallel edges, the longitudinal axis of said opening 115 being set at an angle to the plane of revolution of said reel.

7. In an eyeglass holder, a casing having a spring actuated reel on its interior, a chain

connected to the reel and being passed through an opening provided therefor in the casing, said opening being wedge shaped so as to permit the casing on opposite sides 5 of the opening to engage the chain to hold the latter against the action of the spring of the reel.

In testimony whereof I have hereunto set my hand in the presence of two witnesses.

GEORGE HERBERT CLAPHAM.
